UNITED STATES PATENT OFFICE.

SIMON GROSSMAN, OF PITTSBURGH, PENNSYLVANIA.

TRUNK-CATCH.

1,195,810.

Specification of Letters Patent. Patented Aug. 22, 1916.

Application filed December 28, 1914. Serial No. 379,298.

To all whom it may concern:

Be it known that I, SIMON GROSSMAN, a citizen of the United States, residing at Pittsburgh, in the county of Allegheny and 5 State of Pennsylvania, have invented certain new and useful Improvements in Trunk-Catches, of which the following is a specification.

My invention relates to improvements in 10 trunk catches, and refers particularly to the construction of the catch or hasp used in conjunction with the usual trunk lock.

One object of my invention is the provision of a catch which will permit of the 15 use of a lock for securing the catch and absolutely preventing it from being released without removing the lock used in fastening the catch.

A further object of my invention is the 20 provision of a catch capable of being locked which will also perform the service of a handle in raising and lowering the trunk top or cover.

A further object of my invention is the 25 provision of a catch which will also serve as an additional lock for the trunk and which will be of ornamental appearance, simple, durable and inexpensive of construction and thoroughly efficient and practical in every particular.

With these objects in view my invention consists of a trunk catch, comprising a pivoted hasp or catch, a keeper for engagement with said hasp and a lock for securing the 35 hasp to said keeper.

The invention further consists of a trunk catch embodying novel features of construction and combination of parts substantially as shown, described and particularly defined 40 by the claim.

Figure 1 is a front view of a portion of a trunk equipped with my catches. Fig. 2 is a front view of the catch shown on an enlarged scale. Fig. 3 is a side or edge view 45 of the catch, and Fig. 4 is a vertical central sectional view.

My catch is used upon a trunk A, of usual construction provided with a hasp lock B, of any desired design, and preferably two of

the catches are used disposed near each end 50 of the trunk.

The individual catch consists of the plate C, secured to the cover of the trunk and provided with a loop forming a keeper D, and the plate E, secured to the main portion or 55 body of the trunk and having pivotally mounted at F, therein the hasp G, formed with an opening H, to snugly fit upon or over said keeper D, and a spring J is employed to snap the hasp into engagement 60 with said keeper.

Two or more of the catches are used and it will be noted that the hasp G engages and is retained by the keeper D, and to absolutely lock the hasp, I employ a lock K, of 65 the padlock type whose staple L, is passed through the keeper and thus locks the hasp and forms a further safe guard for the trunk.

It will thus be seen that the catches in 70 conjunction with the usual hasp lock, equip the trunk with a series of locks performing the function of a catch, a lock and a handle for raising and lowering the hinged cover and that in addition to possessing the advantages stated, the catch is ornamental, inexpensive and practical.

It will be understood that the position of my catch may be reversed and also that the catch may be used upon suit cases, boxes, or 80 in fact upon any article where it would perform its function in a practical manner.

I claim:

A trunk catch consisting of a plate secured to one part of the trunk, having a 85 loop projecting therefrom to provide a handle, a plate secured to the other part of the trunk, a casing formed on said plate, a hasp pivoted in said casing and formed with an opening to fit over said handle, a 90 spring engaging the frame of said hasp adapted to receive a locking means.

In testimony whereof I affix my signature in presence of two witnesses.

SIMON GROSSMAN.

Witnesses:

PAULINE NEAMAN,
M. G. EPSTEIN.
